ABSTRACT

A package theft prevention system comprising a mailbox defining an irregularly shaped interior compartment for storage of received packages. The lower portion of the mailbox has an outward, distally tapering wall for anchoring to concrete it is embedded in. The uppermost opening to the mailbox has a package door biased in the closed condition, where, just downward of the package door is a self-closing trap door biased in its closed position. As the package door and the trap door are offset and open in opposing directions, removal of packages from the upper opening is frustrated while receipt by the deliverer is facilitated. A lockable rear door below the upper opening provides access to the interior compartment for the owner.

MAIL AND PACKAGE THEFT PREVENTION DEVICE, SYSTEM, AND METHOD

CROSS-REFERENCE TO RELATED APPLICATION

This application claims the benefit of priority of U.S. provisional application No. 63/482,388, filed 31 Jan. 2023, the contents of which are herein incorporated by reference.

BACKGROUND OF THE INVENTION

The present invention relates to mailboxes and, more particularly, an improved mailbox adapted to prevent theft of packages and mail received therein.

Mail and package theft has soared in concert with the increase in online shopping. Also according to reports, porch piracy is widely regarded as a difficult crime to resolve, with a mere 10% of cases resulting in an arrest by the police. Therefore, a significant number of these incidents remain unsolved.

Conventional mailboxes lack the proper security for preventing mail or packages being stolen as thieves can either take the entire mailbox, break the mailbox, or just steal the packages that do not fit in the mailbox.

As can be seen, there is a need for an improved mailbox adapted to prevent theft of packages and mail received therein.

SUMMARY OF THE INVENTION

The mailbox embodied in the present invention contemplates a full mailbox embedded in concrete approximately two to four feet in the ground.

The present invention mailbox has biased trap door between the package reception point and the interior compartment allowing delivery vendors to insert the package therein by preventing others from removing the package from the same reception point.

The mailbox is dimensioned, weighted, and adapted to prevent a body (even that of a child) from climbing or getting into the mailbox.

The owner can access the packages via a rear lockable door.

The improved mailbox may have an envelope slot located on the front of the mailbox that receives mail by lifting a lid to expose a mail slot.

As such, the improved mailbox of the present invention puts control back into the owner's hand as they need not worry if their mail will be there or not.

In one aspect of the present invention, a package theft prevention system, the system includes the following: a body having an upper portion and a lower portion, wherein the lower portion has a greater cross-section than the upper portion; each portion providing a plurality of walls, wherein at least one wall of the plurality of walls of the lower portion taper distally as it extends from the upper portion so that said wall projects distally from a profile of the upper portion, wherein the lower portion is embedded in concrete so that said wall resists removal of the lower portion from the concrete embedment.

In another aspect of the present invention, the package theft prevention system further includes the following: an upper opening at an upper end of the upper portion; a package door pivotably connected to the upper opening so as to be movable between an open position and a closed position; and a trap door disposed within the upper portion

below the upper opening, wherein the trap door is pivotably movable between an open position and a closed position, wherein the trap door is biased in the closed position, and wherein movement to the open position is in a downward direction, wherein the open position of the package door is in an upward direction, wherein the package door is biased in the closed position; further including a weighted guideline that biases the package door in the closed position, wherein the package door and the trap door are connected, respectively, to opposing walls of the plurality of walls; further including a rear door disposed along a rear wall of the plurality of walls and below the trap door and the package door, wherein the rear door is movable between a locked engagement and an unlocked engagement; further including a mail slot along a front wall of the plurality of walls, wherein the mail slot is disposed at an elevation between the trap door and the rear door; and further including a mail door pivotably associated to the mail slot so as to move between an open disposition and a closed disposition covering the mail slot.

In yet another aspect of the present invention, a method of preventing package theft includes embedding the above-mentioned package theft prevention system in concrete.

These and other features, aspects and advantages of the present invention will become better understood with reference to the following drawings, description, and claims.

BRIEF DESCRIPTION OF THE DRAWINGS

FIG. 1 is a front perspective view of an exemplary embodiment of the present invention.

FIG. 2 is a rear perspective view of an exemplary embodiment of the present invention.

FIG. 3 is a front perspective view of an exemplary embodiment of the present invention, showing a mail door 14 in an open disposition.

FIG. 4 is a front perspective view of an exemplary embodiment of the present invention, showing a package door 20 in a raised condition.

FIG. 5 is a section view taken along line 5-5 in FIG. 1.

FIG. 6 is the section view of FIG. 5 showing the package door 20 in the raised position and a trap door 26 in an open position.

FIG. 7 is a flow chart of a method of customizing an exemplary embodiment of the present invention.

FIG. 8 is a front perspective view of an alternative embodiment of the present invention, showing a mail door 14 in an open disposition.

FIG. 9 is a section view of FIG. 8

DETAILED DESCRIPTION OF THE INVENTION

The following detailed description is of the best currently contemplated modes of carrying out exemplary embodiments of the invention. The description is not to be taken in a limiting sense but is made merely for the purpose of illustrating the general principles of the invention, since the scope of the invention is best defined by the appended claims.

Referring to FIGS. 1 through 7, the present invention may include a mailbox 100 having a body 10 that may be embedded in concrete approximately two to four feet in the ground. The body 10 may include a plurality of walls that define an interior compartment 34 for storing packages or mail. The body 10 and thus the compartment 34 may have an upper portion 40 and a lower portion 50. The cross-

section of the upper portion **40** may be less than a cross-section of the lower portion **50**. While the upper portion **40** may have a uniform cross-section throughout its length, the cross-section of the lower portion **50** may increase as the lower portion **50** extends downward. Specifically, the lower portion **50** may taper distally as it extends downward, thereby forming a wedge, which would make pulling the mailbox **100** from its concrete embedment (not shown) more challenging as the outwardly sloping wall would contact surrounding concrete.

Accordingly, the hollow cross-section of the lower portion **50** is greater than that of the upper portion **40**, thereby the lower portion **50** provides more space for storing mail and packages that may pile up over multiple deliveries. It is understood that other arrangements, dimensions, and shapes are contemplated herein as long as the improved mailbox **100** functions as disclosed herein.

At the upper end of the upper portion **40** is an upper opening **21** that communicates the interior compartment **34** with the external environment. The upper opening **21** may be covered by a package door **20**. The package door **20** may be disposed, at rest, in a sloped oriented. In such an embodiment, the rear wall may be at a higher elevation relative to the front wall, as illustrated in the Figures (though other orientations of the package door **20** and walls, including a horizontal orientation are contemplated even if not shown in the exemplary Figures). The package door **20** may have a handle **22** for moving the package door between an open condition and a closed condition in the sloped orientation. In the open condition, the package door **20** may be in a substantially vertically upward orientation as shown in FIG. 6. The package door **20** may be pivotably connected to the front wall to facilitate its movement between the open and closed conditions.

The package door **20** may have a guideline **24** with weight secure to the package door **20**, preventing it from remaining in the open position after deliveries may be an alternative. The guideline **24** with weight biases the package door **20** in the closed condition.

A trap door **26** may be disposed across a hollow portion of the upper portion **40**. The trap door **26** may be pivotably connected to an inner surface of the upper portion by way of a self-closing hinge **28** so that the trap door **26** is pivotable between a closed position, providing a barrier to the lower portion of the interior compartment **34**, and an open position providing access to the lower portion of the interior compartment **34**. The self-closing hinge **28** may be spring-loaded or otherwise biased in the closed position. In the open position the trap door **26** may be moved to a less than vertically downward orientation, as shown in FIG. 6. The trap door **26** may be disposed just downward of an upper opening of the interior compartment **34**, as shown in FIG. 5. The trap door **26** may be horizontally oriented and disposed just downward of the lowest point of the upper opening.

The pivotable connection point of the package door **20** may be along a wall opposite the self-closing hinge **28**—e.g., the self-closing hinge **28** connection point is located along the rear wall, while the pivotable connection point of the package door **20** may be disposed along the front wall, whereby this opposing arrangement of pivotably biased doors critically makes removing packages from the internal compartment **34** via the upper opening **21** as challenging as possibly, while not frustrating the deliverer from inserting the package into the interior compartment **34** in the first place.

A mail slot **12** may be disposed in the front wall so that it communicates the interior compartment **34** with the exter-

nal environment. The mail slot **12** may be disposed below the lowest point of the trap door **26**. A mail door **14** may be disposed over the mail slot **12** so that the mail door moves between an open disposition and closed disposition covering the mail slot **12**. The movement between the open and closed dispositions may be facilitated by a mail door pull **16**. The mail door **14** may have decorative shingles **18**.

Along the rear wall, a rear door **30** is provided for accessing the lower portion of the interior compartment **34**; thus, the rear door **30** is at a lower elevation than the package door **20**, the trap door **26**, and the mail door **12**. The rear door **30** is movable between an open arrangement and a closed arrangement. In the closed arrangement, the rear door may be locked and unlocked by way of a key. A rear door handle **32** may be provided for facilitating the movement between the open and closed arrangements. A locking device may be associated with the rear door **30** or its pivotable connection so that, in the closed arrangement, the back door **30** may be toggled between a locked condition and an unlocked condition.

In use, a package deliverer may open the package door **20** to the open condition and urge a package past the closed-position-biased trap door **26** and into the interior compartment **34**. Immediately after the package clears the trap door **26** it self-closes.

In certain embodiments, referring to FIGS. 8 and 9, the mail slot **12** may provide an aperture **42**, which is the only opening that communicates with the interior compartment **34** from the “front” of the mailbox **100**. Furthermore, a front trap door **44** may be attached by a spring hinge **28** just upward of the mail slot **12** to the interior front wall of said mailbox **100** so that in the open position, the front trap door **44** covers a portion or an entirety of the mail slot **12**, and the entirety of the aperture **42**. Accordingly, when the mail personnel push a letter or other correspondence through the aperture urges the front trap door **44** is urged back, see FIG. 9, to a closed position, closing off the upper access to the interior compartment **34**.

Different components of the improved mailbox **100** may be made of or comprise brick, wood, metallic materials, plasticized material, or other suitable materials. The relationships between the components are illustrated in the flow chart of FIG. 7. The dimensions and material types may be varied based on need, demand, environmental limitations, aesthetics, and the like.

The present invention may be used to solve the rising problems of porch pirates taking packages and leaving the vendor, delivery service provider and homeowner out in the dark about what to do. Also, the present invention can be used for any products needing extra security with storage.

As used in this application, the term “about” or “approximately” refers to a range of values within plus or minus 10% of the specified number. And the term “substantially” refers to up to 80% or more of an entirety. Recitation of ranges of values herein are not intended to be limiting, referring instead individually to any and all values falling within the range, unless otherwise indicated, and each separate value within such a range is incorporated into the specification as if it were individually recited herein.

For purposes of this disclosure, the term “aligned” means parallel, substantially parallel, or forming an angle of less than 35.0 degrees. For purposes of this disclosure, the term “transverse” means perpendicular, substantially perpendicular, or forming an angle between 55.0 and 125.0 degrees. Also, for purposes of this disclosure, the term “length” means the longest dimension of an object. Also, for purposes of this disclosure, the term “width” means the dimension of

5

an object from side to side. For the purposes of this disclosure, the term "above" generally means superjacent, substantially superjacent, or higher than another object although not directly overlying the object. Further, for purposes of this disclosure, the term "mechanical communication" generally refers to components being in direct physical contact with each other or being in indirect physical contact with each other where movement of one component affects the position of the other.

The use of any and all examples, or exemplary language ("e.g., "such as," or the like) provided herein, is intended merely to better illuminate the embodiments and does not pose a limitation on the scope of the embodiments or the claims. No language in the specification should be construed as indicating any unclaimed element as essential to the practice of the disclosed embodiments.

In the following description, it is understood that terms such as "first," "second," "top," "bottom," "up," "down," and the like, are words of convenience and are not to be construed as limiting terms unless specifically stated to the contrary.

It should be understood, of course, that the foregoing relates to exemplary embodiments of the invention and that modifications may be made without departing from the spirit and scope of the invention as set forth in the following claims.

What is claimed is:

1. A package theft prevention system, the system comprising;

a body having an upper portion and a lower portion, wherein the lower portion has a greater cross-section than the upper portion;

each portion providing a plurality of walls, wherein at least one wall of the plurality of walls of the lower portion tapers distally as it extends from the upper portion so that said at least one wall projects distally from a profile of the upper portion,

5

6

wherein the lower portion is embedded in concrete so that said at least one wall resists removal of the lower portion from the concrete;

an upper opening at an upper end of the upper portion; a package door pivotably connected to the upper opening so as to be movable between an open position and a closed position;

a weighted guideline operatively associated with the package door so that the package door is biased in the closed position;

a trap door disposed within the upper portion below the upper opening, wherein the trap door is pivotably movable between an open position and a closed position; and

a spring hinge operatively associated with the trap door so that the trap door is biased in the closed position, and wherein movement to the open position of the trap door is in a downward direction, wherein the open position of the package door is in an upward direction.

2. The system of claim 1, wherein the package door and the trap door are connected, respectively, to opposing walls of the plurality of walls.

3. The system of claim 2, further comprising a rear door disposed along a rear wall of the plurality of walls and below the trap door and the package door; a locking device operatively associated with the rear door so that the rear door is movable between a locked engagement and an unlocked engagement.

4. The system of claim 3, further comprising a mail slot along a front wall of the plurality of walls, wherein the mail slot is disposed at an elevation between the trap door and the rear door.

5. The system of claim 4, further comprising a mail door pivotably associated to the mail slot so as to move between an open disposition and a closed disposition covering the mail slot.
